UNITED STATES PATENT OFFICE

ABRAHAM LUYSTER AND CULVER P. LUYSTER, OF MUSKEGON HEIGHTS, MICHIGAN

SNOWPLOW

Application filed November 7, 1929. Serial No. 405,402.

This invention relates to snow plows and particularly to a snow plow for clearing roads and the like which may be drawn either by draft animals or by a tractor.

One of the objects of the invention is to provide a snow plow which is adjustable so that paths of different widths may be made.

A further object is to provide means whereby the forward end of the plow may be lifted so as to pass over obstructions such as tracks which the snow plow has to cross.

A further object is to provide means for causing the snow plow to follow a straight course, this means comprising preferably a sled upon which the operator stands and operatively connected to the plow, which sled has snow-cutting runners which will act to hold the plow to its true course.

A further object is to provide a plow which may be easily and quickly taken apart or assembled and when taken apart can be stored in a small space.

Other objects will appear in the course of the following description.

Our invention is illustrated in the accompanying drawings, wherein:—

Figure 1 is a top plan view of a snow plow constructed in accordance with our invention;

Figure 2 is a side elevation thereof;

Figure 3 is a section on the line 3—3 of Figure 2;

Figure 4 is a longitudinal vertical sectional view through the plow showing the lever depressed and the nose of the plow raised;

Figure 5 is a fragmentary longitudinal section through the nose of the plow showing the lever raised and the shoe running over the snow;

Figure 6 is a fragmentary sectional view on the line 6—6 of Figure 2;

Figure 7 is a section on the line 7—7 of Figure 1;

Figure 8 is a sectional view through the spacing cross bar and showing a portion of the sides;

Figure 9 is a perspective view of the rack.

Each side of the plow, as shown in Figures 2 and 3 is composed of two boards 10

and 11 disposed at an angle to each other and held in this position by means of steel braces 12 forged to correspond to the pitch of the boards, these braces being bolted to the side boards by means of bolts 13. Attached to each bottom board is a steel strip 14 fastened by means of wooden screws or the like. This strip is necessary on the lower edge of the bottom board because of the excessive wear at that point. The plow point 15 which is of steel is bolted or otherwise fastened to only one side of the plow, as for instance, by the bolts 16. This point 15 is of steel and is forged to correspond to the angle of the sides. The forward end of the plow point is reinforced by means of the more or less vertically disposed angle iron 17 which may extend to the full depth of the plow point but which as shown, extends only a portion of this depth and is disposed preferably adjacent the bottom of the plow point.

As will be seen from Figure 1, the plow point 15 is connected to the side boards on one side of the plow but on the other side the wing of the plow point is shorter and merely abuts against the ends of the boards 10 and 11.

The plow boards are flexibly connected at the nose by two pairs of overlapping eyes 18, the shanks of which extend through the side boards and receive the counter-sunk nuts 19. These shanks of the eyes 18 pass through tubular spacers or sleeves 20 which bear against the ordinary metallic strips or reinforcing members 21. These spacers keep the eyes spaced from the sides of the plow.

Extending downward through the eyes is a pin 22, thus securing the forward convergent ends of the side boards together, but permitting them to be adjusted toward or from each other.

Means whereby the rear ends of the side boards may be adjusted toward or from each other is illustrated in Figure 8. This means comprises two telescoping pipe sections 23 and 24, the section 24 telescoping within the section 23. Each of these pipe sections at its ends is pivotally connected to ears 25 which are riveted to an adjacent brace 12.

The section 23 is provided with a single hole and the section 24 is provided with a plurality of perforations 26 and a pin 27 may be inserted through the single opening of the member 23 and down through any one of the openings 26. Thus it is obvious that the side boards or wings of the plow may be spaced apart or adjusted nearer to each other as desired.

- 10 A handle is provided comprising, as shown in Figure 3, a cross bar formed in two telescopic sections 28 and 29. Each of these sections at its ends is connected to an elbow 30 which is in turn connected to a vertical pipe 31. Inserted in the lower ends of these pipes are the metal plugs 32, the shanks of which are flattened as at 33 and extend downward to the uppermost side boards 10.

Disposed between the shanks 33 and the side boards 10 are the angular filler blocks 34 and bolts 35 pass through the shanks 33 and through these filler blocks and through the boards 10, thus holding the side boards in place. The handle is thus laterally expandable or contractible with the adjustment of the wings of the plow. There is no necessity of pinning the members 28 and 29 in adjusted relation, however, as all strain is taken up by the adjustable cross bar formed by the members 23 and 24.

Attached to the members 23 and 24 and trailing behind the same is a sled 36 having two forwardly extending angle irons 38 forming draft irons and formed with eyes 37 which loosely surround the tubular member 23 so that the sled may rise and fall. This sled may be formed in any desired manner except that it must be provided with two parallel runners 38. These are formed of angle iron so disposed that one of the flanges of each angle iron extends straight downward as shown in Figure 3 so that these runners will cut into the snow. This will cause the snow plow to follow a straight course as the angle iron runners force into the snow but the operator's weight will have a tendency to keep the snow plow always running straight.

For the purpose of raising the nose of the plow when an obstruction is met with, as for instance, when the plow is about to cross railroad tracks or the like, we provide a lever shown best in Figure 2 and designated 39, this lever being formed of a single piece of strap iron twisted at 40 and welded to a transverse cross bar constituting trunnions and designated 41. This cross bar 41 is inserted in sockets formed in the side boards so that it may have free rotation.

60 The lower end of the lever is angularly bent as at 41 and normally lies flat upon the snow or ice and is preferably of double thickness. Ordinarily this shoe 42 will ride upon the snow as before described but when the handle of the lever is depressed, the shoe

of the lever will be forced downward, thus lifting the forward end of the plow. The lever is held in its adjusted position at its rear end by operating over the rack 43, the rack being provided with the teeth 44 and having the guide iron 45 attached thereto. This rack is bolted in the side boards 10 through the triangular block 46. This lever makes it possible to raise the front end of the plow so as to clear all obstructions. 75 The shoe 42 of the lever may be held down for any desired length of time by engaging the handle of the lever in any one of the notches of the rack 43. This makes it particularly convenient if a series of railway tracks have to be crossed. When the series of tracks have been crossed, the lever will remain in neutral position of its own accord with full length of the shoe running on the snow.

80 The plow may be connected to any suitable draft means, but we have shown for this purpose a clevis 47 formed of metal bent into an approximate V form with a coil 48 formed at the forward end of the V, the rear ends of the legs being hooked and engaging with eye bolts 49 extending through the side boards 10 as shown in Figure 1. This leaves the clevis free to move up or down and at the same time forms 95 a very simple way of connecting the draft animal or draft means to the plow.

90 While, of course, we do not wish to be limited to any particular dimensions, we may say that for the sake of illustration, the plow will have an over-all length of approximately eight feet and an over-all height of nearly three feet.

100 The wings of the plow may be expanded or contracted to make paths of different widths and this adjustment is very readily secured by means shown in Figure 8. The weight of the operator on the sled will force the angle iron runners into the snow so that the plow will tend to run straight at all times. The lever whereby the nose of the plow is lifted or lowered is conveniently disposed with relation to the operator on the sled so that the nose of the plow at any moment may be raised if desired. It will be 115 obvious that by withdrawing the pin 22 and removing the members 23 and 24 from their engagement with each other, the two sections of the plow may be readily separated so that the plow may be stored in 120 compact form without taking up very much room and that by this means the plow may be as readily removed.

125 This plow will be made preferably in two sizes and will be made of steel or wood.

We claim:

1. In a plow of the character described, forwardly convergent wings pivotally engaged with each other at their forward ends, an adjustable cross bar engaging the wings 130

of the plow and holding them in transversely adjusted relation, a sled engaged with the cross bar and trailing from the same, and a handle bar formed of two telescopic sections extending transversely across the plow above the sled and having members engaged with the wings of the plow.

2. In a plow of the character described, two convergent wings spaced apart at their forward ends an appreciable distance, a plurality of eyes attached to each wing at the forward ends thereof and extending toward each other, the eyes of one wing overlapping the eyes of the other, a pintle insertible through said eyes to pivotally connect the two wings of the plow to each other, means adjacent the rear end of the plow whereby the wings may be held in adjusted relation nearer to or further from each other, and a metallic nose V-shaped in cross section permanently attached on one side to one wing of the plow and projecting forward therefrom but unattached to the other wing of the plow and at the rear end closing the gap between said wings.

3. In a snow plow, forwardly convergent wings, each wing consisting of an upper board and a lower board disposed in angular relation to each other, braces holding the boards in angular relation to each other, means pivotally engaging the wings at their forward ends, means adjustably connecting the wings at their rear ends whereby the width of the plow may be varied, a sled operatively connected to the plow and disposed between the wings, a telescopic handle bar formed of two sections, each section being operatively connected to one of the wings, and a plow point connected to one of the wings of the plow at the forward end thereof, but unconnected to the other wing of the plow.

4. In a snow plow having forwardly convergent wings, means for raising the forward end of the plow comprising a lever disposed between the wings of the plow and pivotally mounted upon said wings adjacent the nose of said plow, the upper end of the lever extending rearwardly, the forward end of the lever extending downward from said pivot point and then extending rearward and adapted to travel over the surface of the snow, that portion of the lever below the pivot being flattened to form a shoe, and extending rearward and then extending forward and upwardly.

5. In a plow of the character described, two convergent wings spaced apart at their forward ends and pivotally and detachably connected to each other whereby the wings may be shifted into or out of a more or less convergent position, means adjacent the rear end of the plow whereby the wings may be held in angularly adjusted relation nearer to or further from each other and a metallic

nose V-shaped in cross section permanently attached on one side to one wing of the plow and projecting forward therefrom but unattached to the other wing of the plow and extending to the adjacent edge of this wing said nose closing the gap between the wings.

In testimony whereof we hereunto affix our signatures.

ABRAHAM LUYSTER.
CULVER P. LUYSTER.
